UNITED STATES PATENT OFFICE.

JOHN COLLINS CLANCY, OF PROVIDENCE, RHODE ISLAND, ASSIGNOR TO THE NITROGEN CORPORATION, OF PROVIDENCE, RHODE ISLAND, A CORPORATION OF RHODE ISLAND.

METHOD OF FORMING NITROGEN-HYDROGEN MIXTURES.

Application filed February 18, 1922. Serial No. 537,530.

This invention relates to an improved method of forming nitrogen-hydrogen mixtures, one object of which is to provide a method for readily forming a nitrogen-hydrogen mixture containing the gases in any desired proportions.

Another object of the invention is to conserve the heat developed by the combustion of the gases for raising the temperature of the combustion chamber to such a point as to insure a complete combination of the oxygen of the air with hydrogen.

A further object of the invention is to provide an additional purifying agency for removing any traces of oxygen from the gas mixture.

Other objects and advantages of the invention relate to certain novel steps and combinations of steps in the effectuation of the process as will be more fully set forth in the detailed description to follow.

In obtaining nitrogen-hydrogen mixtures by processes which permit the utilization of atmospheric air as a source of supply for the nitrogen content of the mixtures, it is frequently desirable to obtain mixtures containing varying proportions of the gases and to eliminate from the gases any traces of oxygen which may be present in the air used in forming the mixture. In accomplishing these objects I propose to obtain a substantially pure nitrogen, or nitrogen together with a less quantity of hydrogen than is desired in the ultimate mixture, by burning out the oxygen content of the air and adding thereto substantially pure hydrogen which may be heated by the heat generated during the combustion of the oxygen content of the air to combine with any traces of unburned oxygen remaining in the gases.

In the accompanying drawings is represented an example, in diagrammatic form, of an apparatus adapted to perform the process which forms the subject of the present invention.

In the annexed drawings 1 designates an air reservoir provided with an inlet pipe 2 and an outlet pipe 3 provided with a valve 4 and communicating with the interior 5 of a combustion tube 6. A hydrogen supply

pipe 7 has branches 8 and 9 extending therefrom, the branches being provided with valves 10 and 11 respectively. The branch 8 extends within the combustion tube 6 at a point adjacent to the point of entry of the pipe 3 therein.

The tube 6 serves as a combustion chamber for the burning of the oxygen content of the air admitted through the pipe 3 with the hydrogen admitted through the pipe 8, the combustion commencing at a point adjacent to that at which the pipes 3 and 8 enter the tube 6 and the flame extends forwardly therefrom towards the open end of the tube 6 thus heating the tube 6 to a high temperature and raising the temperature of the excess hydrogen admitted through the pipe 9 into the concentric passage 12 surrounding the tube 6 within the casing 13 which surrounds the tube 6 throughout the major portion of its extent.

The concentric passage 12 communicates with the passage 5 at the open end of the tube 6 whereby the excess hydrogen entering the passage 12 from the pipe 9 after being heated by the heat generated by the burning gases in the tube 6 comes into direct contact with the hot combustion products issuing from the open end of the tube 6 to combine with any excess oxygen remaining uncombined in the gases issuing from the tube. Thus the normal heat generated by the burning of the gases as they enter the tube 6 and mingle together therein is augmented by the heat absorbed by the tube 6, which becomes highly heated during the combustion, and the temperature is raised to such a point as to insure complete combustion of the oxygen content of the air at all times and highly heat the excess hydrogen entering the concentric passage 12 so as to utilize such hydrogen if necessary to combine with any traces of oxygen which may be supplied to the tube 6 through the pipe 3 in excess of the quantity with which the hydrogen entering the tube 6 through the pipe 8 will combine. The tube 6 is of comparatively small diameter ranging preferably from one to two inches in diameter while the tube 13 is also of relatively small diameter preferably from two and one half

to three and one half inches in diameter. The use of a combustion chamber having a relatively small diameter as above mentioned facilitates the combustion since it serves to confine the heat of combustion within a relatively restricted space, thus preventing the diffusion of the heat generated and raising the temperature to such a point as to greatly aid in the combustion of the gases and preventing any of the oxygen content of the air from passing over without being combined with hydrogen to form water vapor. This conservation of the heat may be increased if desired by covering the tube 13, and if desired adjacent portions of the system, with a heat insulating covering of asbestos or the like as indicated at 14 although the use of such insulating covering is not essential to the successful operation of the apparatus.

A pipe 15 connects the end of the tube 13 with a casing 16 which contains finely divided metal, such as finely divided copper, iron or the like, as indicated at 17, for a purpose which will be more fully described hereinafter. A pipe 22 extends from the pipe 15 adjacent to the end of the tube 13 and is provided with a valve 23 which may be opened at the commencement of the operation to allow the gases to be ignited, the flame applied thereto immediately flashing back to the base of the tube 6 where the air and hydrogen enter and mix together. After the gases have been ignited the valve 23 may be closed and the products of combustion of the gases passed into the system. In igniting the gases in the tube 6 the valve 23 is opened and the valves 4 and 10 opened to permit air and hydrogen to enter the tube 6 through the pipes 3 and 8 the valve 11 remaining closed. After the gases are ignited at the end of the pipe 22 the flame immediately flashes back to the base of the tube 6 and the valve 23 may then be closed. The valve 11 remains closed until combustion is well under way in the tube 6 when it may be opened to admit hydrogen to the passage 12.

The connections between the pipes 3, 8, 9, 15 and 22 and the tubes 6 and 13 are preferably welded to prevent any possible escape of gas therethrough. The tubes 6 and 13 may be advantageously formed of ferro-chromium alloy or other suitable heat resistant material capable of withstanding the high temperatures to which they are subjected.

While the preferred dimensions of the tubes 6 and 13 have been given in order to indicate to those skilled in the art dimensions which have been found to serve the purpose admirably in practice it is to be understood that the invention is not limited to the use of tubes of the dimensions indicated since considerable variation therein is

permissible under varying conditions of operation.

A pipe 25 connects the base of the casing 16 with a cooling coil 26 contained in a condenser 27, where the water vapor formed by the combination of the oxygen of the air with the hydrogen may be condensed, the coil 26 being cooled by means of a supply of water entering the condenser through the pipe 29 and discharged therefrom through the pipe 30. The mixed gases and water of condensation pass from the condenser through the pipe 31 to permit the water to enter the tank 32 while the gaseous mixture passes through the pipe 33 to the gasometer 34 from which it may be drawn by the pump 35, through the pipe 36 and forced under pressure into the storage tank 37.

A drip pipe 40 is provided for withdrawing the condensed water from the tank 32, and a valve 41 is located therein for manipulation in withdrawing the water from the tank as necessity may require.

From the storage tank 37 the gas mixture passes through a pipe 45 to a purifying apparatus 46 where it may be passed through suitable purifying agents for removing traces of such impurities as remain in the gases preparatory to being fed into the synthesizing chamber of an ammonia synthesis apparatus or employed for any other desired purpose, the flow of the gases from the storage tank being regulated by means of the valve 48.

It is to be understood that while I have shown the chamber 5 as that in which the oxygen content of the air is removed by combustion with hydrogen and the excess hydrogen as entering the outer chamber 12 where the heat developed by the combustion of the oxygen of the air and hydrogen in the chamber 5 preheats the excess of hydrogen to enable it to unite with any remaining traces of oxygen from the air, I may reverse the method of operation by leading the air and hydrogen mixture into the chamber 12 and employ this outer chamber as the main combustion chamber while leading the pipe 9 into the chamber 5 to supply the excess hydrogen thereto and preheat the same through the aid of the heat developed by the combustion of the oxygen of the air with the hydrogen in the outer chamber. The provision of the metallic copper in the casing 16 while advantageous for the purpose of removing traces of oxygen which may be present in the gaseous mixture is not essential under all conditions and may be dispensed with when found expedient.

In the carrying out of my improved process by means of the apparatus shown and described, hydrogen is admitted into the pipe 8 by opening the valve 10 and then air is admitted through the pipe 3 by opening

the valve 4. The valve 23 is then opened and the mixture ignited at the end of the pipe 22 whereupon the flame flashes back into the tube 6 and the hydrogen admitted through the pipe 8 combines with the oxygen content of the air to form water vapor, substantially removing the oxygen content from the air thus admitted.

10 Certain variations in the method of procedure may be employed depending upon the conditions of operation and the percentages of nitrogen and hydrogen desired in the resulting mixture. For example I 15 may admit a certain flow of air through the pipe 3 to the burner and admit only sufficient hydrogen through the pipe 8 to combine with the oxygen content of the air admitted through the pipe 3, thus forming 20 after the combustion substantially pure nitrogen which will pass out of the combustion chamber through the pipe 15 mingled with the water vapor formed as a result of the combustion. In order to obtain a 25 nitrogen-hydrogen mixture of any desired proportions I pass hydrogen through the pipe 9 into the passage 12 by opening the valve 11, after the combustion of the gases in the tube 6 has proceeded sufficiently to 30 heat the parts to such a point as to properly preheat the excess hydrogen. Then by varying the quantity of hydrogen admitted to the passage 12 I may obtain a nitrogen-hydrogen mixture in any desired proportions 35 and by regulating the valve 11 may vary these proportions as desired. The hydrogen from the passage 12 mingles immediately with the hot gases issuing from the tube 6 to effect elimination of any traces of 40 oxygen which may be present in the gases and form a nitrogen-hydrogen mixture of the desired proportions.

The proportioning of the gases as above outlined may be varied somewhat by admitting a certain flow of air through the pipe 3 by manipulation of the valve 4 and admitting at the same time such a flow of hydrogen through the pipe 8 as will be more than sufficient to combine with the 50 oxygen content of the air admitted through the pipe 3 whereby, when the gas mixture is ignited as previously described, the gases issuing from the tube 6 will consist of a nitrogen-hydrogen mixture together with 55 water vapor formed as a result of the combustion.

The hydrogen content of this mixture may be increased to any desired degree by the addition of hydrogen admitted through 60 the pipe 9 to the passage 12.

From the above description it will be understood that it is possible by my improved method to obtain a nitrogen-hydrogen mixture containing the gases in any de-

sired proportions either within the limits 65 within which the excess hydrogen will readily combine with all the oxygen of the air to completely eliminate the same or measurably beyond those limits, and the excess hydrogen gas preheated without the use of 70 external power but by means of the heat generated during the combustion of the oxygen content of the air. By means of the relatively constricted passages 6 and 12 as well as the heat insulating covering 14 the 75 heat of combustion is conserved and utilized both in the complete combustion of the oxygen content of the air and the preheating of the hydrogen.

The gas mixture thus obtained is passed 80 through the pipe 15 into the casing 16 where it heats the finely divided copper or other metal 17 and the heated copper removes any traces of oxygen which may chance to be present in the mixture, the copper being 85 again reduced by the hydrogen in the mixture and the traces of oxygen taken up thereby being converted into water vapor by the hydrogen. The water vapor present in the gases as a result of the elimination of 90 the oxygen is condensed in the condenser 27 and passes into the tank 32 from which it may be withdrawn at suitable intervals while the nitrogen-hydrogen mixture freed from oxygen and water vapor passes to the 95 gasometer 34 and the storage tank 37 from which it may be drawn from use as desired.

The air and hydrogen supplied to the burner are preferably under slightly super-atmospheric pressure to force them through the system but they may be caused to traverse the system by means of the pump 35 or other pumping apparatus located elsewhere in the system.

While I prefer to employ finely divided copper in the casing 16 to remove any slight traces of oxygen which may remain in the gases since copper combines with oxygen readily when heated and is also readily reduced by the hydrogen to form water vapor and return the metal to its initial condition, I may employ finely divided iron or other suitable material for this purpose.

From the above description it will be understood that I have devised a novel method of forming nitrogen-hydrogen mixtures by utilizing atmospheric nitrogen, that by means of my improved method any desired proportions of nitrogen and hydrogen 120 may be present in the ultimate mixture, and with suitable conservation of the heat of combustion the heat may be utilized for facilitating the combustion of the gases as well as preheating the excess hydrogen and eliminating any traces of oxygen present in the gases and heating the copper or equivalent metal contained in the receptacle 125

16 to furnish an additional insurance
against any traces of uncombined oxygen
being present in the final product.

What I claim is:—

1. The process of producing a nitrogen-hydrogen mixture containing the gases in any desired proportion, which comprises, burning the oxygen content from atmospheric air by means of hydrogen to form nitrogen substantially free from hydrogen, preheating an additional quantity of hydrogen by means of the heat generated by the combustion of the oxygen content of the air with hydrogen, and adding a sufficient quantity of the preheated hydrogen to the gas obtained from the burning out of the oxygen content of the air to remove any traces of oxygen remaining in the gases and form a mixture containing the desired proportions of nitrogen and hydrogen. 65
2. The process of producing a nitrogen-hydrogen mixture containing the gases in any desired proportion, which comprises, burning the oxygen content from atmospheric air by means of hydrogen to form nitrogen substantially free from hydrogen, preheating an additional quantity of hydrogen by means of the heat generated by the combination of the oxygen content of the air with hydrogen, adding a sufficient quantity of the preheated hydrogen to the gas obtained from the burning out of the oxygen content of the air to remove any traces of oxygen remaining in the gases and obtain a mixture containing the desired proportions of nitrogen and hydrogen, and passing the mixture thus obtained into contact with a heated metal to remove any traces of oxygen present in the mixture. 70
3. The process of producing a nitrogen-hydrogen mixture containing the gases in any desired proportion, which comprises, burning the oxygen content from atmospheric air with excess hydrogen to form a nitrogen-hydrogen mixture containing less than the desired proportion of hydrogen, preheating an additional quantity of hydrogen by means of the heat generated by the combustion of the oxygen content of the air with hydrogen, and adding a sufficient quantity of the preheated hydrogen to the gas obtained from the burning out of the oxygen content of the air to form a mixture containing the desired proportions of nitrogen and hydrogen. 75
4. The process of producing a nitrogen-hydrogen mixture containing the gases in any desired proportion which comprises, burning the oxygen content from atmospheric air with excess hydrogen to form a nitrogen-hydrogen mixture containing less than the desired proportion of hydrogen, preheating an additional quantity of hydro- 80
- gen by means of the heat generated by the combustion of the oxygen content of the air with hydrogen, adding a sufficient quantity of the preheated hydrogen to the gas obtained from the burning out of the oxygen content of the air to form a mixture containing the desired proportions of nitrogen and hydrogen, and passing the mixture thus obtained into contact with a heated metal to remove any traces of oxygen present in the mixture. 85
5. The process of treating gases, which comprises, burning the oxygen content from atmospheric air in the presence of an excess of hydrogen to form a nitrogen-hydrogen mixture containing less than the desired proportion of hydrogen, and preheating an additional supply of hydrogen to remove any traces of oxygen remaining in the gases by means of the heat generated by the combination of the oxygen content of the air with hydrogen. 90
6. The process of treating gases, which comprises, forming a gaseous mixture composed principally of nitrogen and hydrogen by causing the oxygen content of atmospheric air to unite with hydrogen, heating a quantity of metal by means of the heat generated by the combination of the oxygen content of the air with the hydrogen, and passing the said mixture over the heated metal to remove traces of oxygen which may be present therein. 95
7. The process of forming a nitrogen-hydrogen mixture, which comprises, burning out the oxygen content from a continuous supply of atmospheric air by means of hydrogen, transferring a portion of the heat generated by the combustion of the oxygen content of the air to additional hydrogen to raise the temperature thereof sufficiently 100 to remove traces of oxygen from the resulting gases when mixed therewith, and then combining the gases obtained as the result of the burning out of the oxygen content of the air with a sufficient quantity of the heated hydrogen to secure a mixture containing the desired proportions of nitrogen and hydrogen. 105
8. The process of forming a nitrogen-hydrogen mixture, which comprises, burning the oxygen content of atmospheric air with excess hydrogen to form a nitrogen-hydrogen mixture, heating an additional supply of hydrogen by means of the heat generated by the burning of the oxygen content of the air, and bringing the heated hydrogen into said nitrogen-hydrogen mixture at a point in proximity to that at which the combustion of the oxygen content of the air is taking place. 115
9. The process of forming a nitrogen-hydrogen mixture, which comprises, burning the oxygen content of atmospheric air with excess hydrogen in a relatively restricted 120

space to form a nitrogen-hydrogen mixture and at the same time conserve the heat of combustion, heating an additional supply of hydrogen by means of the heat generated by
5 the burning of the oxygen content of the air, and bringing the heated hydrogen into said nitrogen-hydrogen mixture at a point in

proximity to that at which the combustion of the oxygen content of the air is taking place.

10

In testimony whereof I have affixed my signature.

JOHN COLLINS CLANCY.
